UNITED STATES PATENT OFFICE.

EDWARD B. WESTON, OF DAYTON, OHIO.

CONVERTIBLE SHELVES AND TABLE.

SPECIFICATION forming part of Letters Patent No. 603,715, dated May 10, 1898.

Application filed April 15, 1897. Serial No. 632,197. (No model.)

To all whom it may concern:

Be it known that I, EDWARD B. WESTON, a citizen of the United States, residing at Dayton, in the county of Montgomery and State 5 of Ohio, have invented certain new and useful Improvements in Convertible Shelves and Tables, of which the following is a full, clear, and exact description, reference being had to the accompanying drawings, forming part of 10 this specification.

My invention relates to that class of structures in which a series of shelves are arranged to be readily and easily adjusted into a horizontal table or a series of steps at any desired 15 angle or into vertical shelves for the ready and convenient display of goods or for such other purposes as may be desired.

In convertible shelves and tables as heretofore constructed it has been found difficult to 20 obtain a solid substantial table, because the shelves when brought into the same horizontal plane have nothing to support them except the side arms to which they are pivoted, and unless these side arms are constructed 25 of such heavy stout material as to very considerably add to the expense and cumbersomeness of the device when pressure or weight is applied to the outside shelf the side supports are not sufficient to hold the shelf from tipping slightly and destroying the even flat surface desired. In fact within the limits of 30 cheapness and simplicity of structure required no such convertible shelves and tables have yet been constructed, so far as I am 35 aware, which overcome this objection. Moreover, with the locking devices heretofore in use on these devices, which have been either hooks, sustaining-arms, or bolts entering notches formed at intervals in the frame or 40 on the shelves, there are only a fixed number of adjustments for the device, and in a short time the wear on the parts causes undue play and the shelves cannot be fixed absolutely in any desired position. It has also been found 45 difficult to obtain proper rigidity for the shelves within the limits of lightness and cheapness when adjusted at an angle or to obtain a smooth even flat surface for the table when adjusted horizontally. It is to over- 50 come these objections that my invention is particularly directed; and it consists, first, in an arrangement of stops on each shelf

whereby the adjoining shelf may be supported; second, in a locking device which enables me to hold the shelves rigidly and securely in any desired position without any liability of the parts wearing loose and affecting the substantial character of the tables or shelves, and, third, in the supporting device for the outermost shelf, whereby all liability 60 of the tipping of the shelf will be avoided.

It is also my aim to arrange the shelves in as open a manner as possible, so that the goods displayed on the shelves may be seen from as many points of view as possible, and 65 so that the goods may be placed on the shelves from the sides as well as from front and rear. This I accomplish by providing only one supporting-bar at each side instead of a pair of bars, such as are usually employed. 70

In the drawings, Figure 1 is a perspective view of my invention adjusted as a horizontal table. Fig. 2 is a vertical section through the shelves when adjusted at an angle. Fig. 3 is a front elevation when adjusted in a vertical position. Fig. 4 is a side elevation of same. Fig. 5 is a cross-section on the lines 55 of Fig. 3, looking upward. Figs. 6, 7, and 8 are details showing the locking device of the outer shelf. Fig. 9 is a perspective view 80 of one of the brackets for the fixed shelf, somewhat enlarged.

A are the supports or frames for sustaining the shelves, provided with casters, when desired, for convenience in moving and connected together by brace-rods *a a* to give 85 strength and stability to the framework.

B B are the shelves, having secured along the side edges metallic bars or strips *b b*, the inner ends of which are provided with lugs 90 *c c*, which lock within the next succeeding notches *d d*, cut in the other end of these strips, and which lugs thus form stops for the next succeeding shelf to rest upon when the shelves are adjusted as a table. Each of these bars 95 *b b* is also provided with ears *e e* at or near the center, and by these ears each shelf, except the central one, is pivoted to the side rods or bars C C. The strips *b* of the central shelf are provided with bracket-plates *ff* and 100 *g g*, by means of which the central shelf is secured rigidly to the supports at the desired height of the horizontal table. One set of these brackets, *ff*, extends out above on a level

with top surface of the fixed shelf, while the other, *g g*, extends below the level of the under surface of this shelf, so that when the shelves are adjusted as a table, as hereinafter described, the brackets *f f* will serve as a rest or stop for the upper edge of the side rods *C C*, while the other set of brackets *g g* will serve as a rest and stop for the lower edge of these side rods. The strips *b' b'* of the fixed shelf instead of having ears for the pivoting of the side rods *C C* thereto carry in place of the ears circular plates or disks of suitable size *h h*, provided with radial ratchet-teeth *ll* on the faces thereof.

15 *m m* are corresponding disks provided with radial teeth to intermesh with the fixed plates *h h* and also with a central groove or recess on the outer surface thereof, within which the side bars *C C* fit. Passing through the 20 side bars *C C* and these intermeshing toothed plates *h m* and underneath the central shelf is a rod *D*, provided with a head *n* at one end bearing against one side of the rod *C* and screw-threaded at the other end and carrying 25 an adjustable hand-wheel *E* thereon bearing against the outer surface of the other side rod. It will be evident from this construction that when the hand-wheel is tightened the pressure on the side bars *C C* will tightly 30 lock together the intermeshing plates *h m*, and thus lock the bars and shelves in any desired position. It will be further evident that with small intermeshing teeth the different positions of adjustment will be greatly 35 increased and that wear or looseness of the parts is at once taken up by the adjustment of the hand-wheel, a point of considerable importance in devices of this kind, the advantages of which have already been commented upon.

In order to hold the shelves always in a horizontal position and to serve as a brace and additional support, I provide lugs *p p*, secured to the under surface of each shelf at or near 45 the center at the back and extending out beyond the rear edge of the shelves with a horizontal upper bearing-surface *r r*. To these lugs are pivoted the bar or rod *F*. The lugs *p p*, in addition to serving as means for pivoting the rod *F* to the shelves, also furnish 50 with their horizontal upper edges *r r* rests or stops for the shelves when adjusted as a table, the front edges of the shelves resting on these stops, as will be seen from an inspection of Fig. 2, and thus we have three stops or rests for each shelf at the center upon the lugs *p p* and at each end on the lugs *c c*. Thus for any weight except on the inner edge of the outermost or lowest shelf the shelves 55 have sufficient rest and support to make a firm and rigid table with a smooth close-jointed upper surface. Of course it will be understood that the shelves are located such a distance apart that the rear edge of one 60 shelf will fit closely and snugly against the front edge of the next shelf. For the lowest shelf, however, to prevent its tipping, it is ad-

visable to have some additional means of support. This is obtained by forming lugs *c c* on the lowest shelf, as shown in Fig. 6, with a downward extension *s* and a shoulder *t*. Pivoted on the inner face of the rods *C C*, opposite the point of contact of the lower shelves, are the catches *w w*, carrying a square shoulder *y*, which when the shelves 75 are swung down into table position catches under the lug *s* and comes to rest against the shoulder *t*, thus holding up and locking securely the lowest shelf against any liability to tip slightly under pressure. When the 80 shelves are to be adjusted into an angular or vertical position, these catches are released, after which they swing out of the way, except when the shelves are brought into a horizontal or table position, when these catches 85 swing by their own weight into position under the lugs *s*.

As the rear bar *F* is pivoted outside the rear edge of the shelves I prefer to make the uppermost shelf somewhat wider than the 90 others or to add a strip *a'* to the uppermost shelf to cover and conceal the lug-pivot and the end of the rod *F*.

It hardly needs mention, but it will be evident from the construction described that, 95 the shelves *B B* being pivoted by the bars *C* and *F* to the horizontally-fixed center shelf, when the band-wheel *E* is loosened the shelves can be swung into any desired position and that as the pivotal distances between the 100 shelves remain constant the swinging shelves will retain their horizontal position parallel to the central shelf.

It will be noticed that in the above construction the fixed shelf is the central one. 105 Of course it can make no difference in the principles of my invention whether the same number or a greater or less number of pivoted shelves are located above and below the fixed shelf; nor can it affect the essence of 110 the invention even if all the shelves are pivoted, so long as the side supporting-bars are pivoted to the supports. For convenience of construction the strips *b b*, carrying the brackets *f f* and *g g*, by means of which they can 115 be secured to the supports, also carry the central shelf; but the central shelf could be pivoted like the other shelves immediately above the brackets and the fixed shelf be omitted altogether without departing from 120 the spirit of my invention.

Having thus described my invention, what I claim, and desire to secure by Letters Patent, is—

1. In a convertible shelf and table, the combination, with a series of pivoted shelves, a fixed shelf, and suitable supports therefor, of single side bars pivoted on the supports and to the shelves at or near the middle of the sides thereof, and a rear bar, pivoted to 125 the shelves at or near the middle of the back portion thereof, with means for locking said pivoted parts, whereby the pivoted shelves may be swung in alignment with the fixed 130

shelf and locked in any desired position, substantially as shown and described.

2. In a convertible shelf and table, the combination, with suitable supports, of a series 5 of shelves, with bars pivoted thereto and to the supports, radially-toothed plates on the supports, with corresponding tooth-plates on the bars at their pivotal connection therewith and a rod, with means for tightening same, 10 passing through said locking-plates, whereby same may be drawn together for locking the device in any desired position, substantially as shown and described.

3. In a convertible shelf and table, the combination, with suitable supports, of a series 15 of shelves with bars pivoted thereto and to the supports, said shelves carrying lugs at the rear, to receive and serve as a rest for the next succeeding shelf, with locking device 20 therefor, whereby said shelves may be converted into a rigid and secure horizontal table, substantially as shown and described.

4. In a convertible table and shelf, the combination, with suitable supports, of a series of shelves with side bars pivoted thereto, and 25 a rear bar pivoted to the shelves, said shelves carrying lugs at the rear corners and a lug at or near the center of the rear edges thereof to which said rear bar is pivoted, said lugs forming stops or rests for the next succeeding shelf, substantially as shown and described. 30

5. In a convertible shelf and table, the combination, with suitable supports, of a series of shelves with bars pivoted thereto and to 35 the supports, catches pivoted to said bars at the meeting-point of the two lowest shelves, shaped to catch under the lowest shelf when adjusted as a table to hold the same rigidly in place, substantially as shown and described. 40
